COMBINED SERVING CONTAINERS AND HOLDER THEREFOR

James B. Swett, Barrington, and Harold P. Ashton, Providence, R.I., assignors to Dart Industries Inc., Los Angeles, Calif.

Filed Aug. 24, 1970, Ser. No. 24,678

Term of patent 14 years

Int. Cl. D7—01

U.S. Cl. D44—1

FIG. 2

FIG. 3

FIG. 4

FIG. 1 is an exploded perspective view of the combined serving containers and holder therefor showing our new design;

FIG. 2 is a bottom plan view of one of the serving container members;

FIG. 3 is a bottom plan view of our combined serving containers and holder therefor; and

FIG. 4 is a front edge elevational view thereof.

We claim:

The ornamental design for combined serving containers and holder therefor, substantially as shown.
